[57] CLAIM

The ornamental design for a tongue brush, as shown and described.

DESCRIPTION

FIG. 1 is a perspective view of a tongue brush showing my new design;

FIG. 2 is a left side view, the right side being a mirror image view thereof;

FIG. 3 is a front elevational view thereof;

FIG. 4 is a rear elevational view thereof;

FIG. 5 is a top plan view thereof; and,

FIG. 6 is a bottom plan view thereof.

The phantom lines depicted in FIGS. 1 and 6 are for more clearly illustrating the environment in which the trim piece is used. The phantom lines are for illustrative purposes only and form no part of the design.
